UNITED STATES PATENT OFFICE

JOHN NICHOLAS PERKINS, OF RICHMOND, VIRGINIA

VALVE-OPERATING MECHANISM

Application filed April 9, 1930. Serial No. 442,919.

My invention relates to means for silencing the action of the valve mechanism of internal combustion engines and the like, and it particularly has for its object to provide a simple, inexpensive device that can readily be installed in new or old engines and will effectively eliminate noise.

Further, it is an object to provide means to take up wear in the movement-transmitting means that conveys the action of the cam shaft to the valve.

Further, it is an object of the invention to provide a device to be interposed between the cam shaft and the valve which will maintain a continuous uninterrupted metallic connection between the cam shaft and the valve, thus enabling the elimination of the clearance space heretofore usually left between the valve tappet and the valve stem or push rod as the case may be.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawing, in which:

Figure 1 is a vertical longitudinal section illustrating one embodiment of the invention, the parts being in the position they assume when the cam has raised the tappet to hold the valve open.

Figure 2 is a similar view with the parts in the position they assume when the valve is closed.

Figure 3 is a perspective view of the inner or compensating unit.

Figure 4 is a horizontal section on the line 4-4 of Figure 1.

Figure 5 is a horizontal section on the line 5-5 of Figure 2.

Figure 6 is a horizontal section on the line 6-6 of Figure 1.

Figure 7 is an inverted plan of the compensating unit.

Figure 8 is a vertical longitudinal section 50 of a modified form of my invention.

Figure 9 is a perspective view of the inner or compensating unit of the form shown in Figure 8.

Figure 10 is a horizontal section on the line 55 10-10 of Figure 8.

In the drawing, in which like numerals of reference indicate like parts in all of the figures, 1 represents the cam shaft, 2 the cam, and 3 the bearing for the tappet. The tappet consists of an outer shell 4 having a cam-engaging end 5, in which shell there is located the inner or compensating unit. This unit is composed of the lower section 6 having a bore 7 and a counterbore 8 and being provided 60 with concave ball seats 9 on the face or end which opposes the upper section 10 of the unit. 65

The upper section 10 of the unit has a stem 11 which projects into the bore 7 and counterbore 8, and it also has a recess 12, the purpose of which will presently appear. The stem 11 has its end slotted as at 13 to receive one end of the torsion spring 15 whose other end is located in the slot 14 of the section 6. 75

A cross pin 16 carried by the section 6 extends into the slot 12 and serves as a stop to limit swivelling motion of the sections 6 and 10 on their common axis with respect one to 80 the other. The upper section 10 has concave ball seats 17 and carries an adjusting screw 18 whose head 19 is adapted to contact the valve stem 21 (or push rod as the case may be), the adjusting screw 18 being held 85 by a jam nut 20.

22 designates balls located between the concave ball seats 9 and 17 respectively and continuously lying in contact with said seats.

In the embodiment of the invention illus- 90

trated in Figures 6 to 8 inclusive, it will be seen that the inner unit is composed of the lower section 23 having concave ball seats 24 and a bore 25, while the upper section 26 has lugs 27 provided with concave ball seats 28, the spaces 29 between the lugs 27 permitting the projection of pins 30 carried on the lower section 23 and cooperating with those pins to limit the rotational or swivelling motion of the sections 23 and 26 on their common axis with relation one to the other.

The upper section 26 also has a recess 31 in which and in the bore 25 a torsion spring 33 lies, the spring having its ends anchored to the respective sections 23 and 26 by pins 32.

Balls 34 lie between the concave seats 24 and 28 respectively and are in continuous contact therewith. The upper section 26 of the inner unit is tapped at 35 for the reception of the usual adjusting screw 18, the construction of which may be the same as the preceding embodiment of the invention, as may also be the construction of the member 4.

In both embodiments of the invention it will be observed that the inner unit is fitted into the shell 4 and rests on the bottom 5, the inner unit being free to turn in the shell 30 on its longitudinal axis.

In both embodiments of the invention also it will be observed that the ball seats of the upper and lower sections are struck on a radius of greater length than the radius of the balls 22 or 34 as the case may be so that the seats 9, 17 or 24, 28 as the case may be, operate in connection with the balls as camming elements, maintaining a metallic thread connection between the upper and lower sections of the inner unit while permitting those sections to move along the direction of their common axis toward and from one another to compensate for the expansion and contraction and for any lag in movement of the parts of the valve operating mechanism, thereby maintaining a continuous metallic train of elements from the cam shaft to the valve itself and eliminating the tap due to metallic contact between parts for clearance now so common in internal combustion engines.

From the foregoing description, taken in connection with the accompanying drawing, it is thought the construction, operation and advantages of my invention will be clear to those skilled in the art to which it relates, and I desire it understood that slight changes in the details of construction may be made without departing from the spirit of the invention or the scope of the appended claims.

What I claim is:

1. In valve mechanism wherein is provided a valve and an actuating cam shaft, and a connection between said valve and cam shaft; said connection including a tubular

outer unit and an inner unit fitted into the outer unit, said inner unit comprising two axially aligned sections, a torsion spring connecting said sections, means limiting the movement of one section relatively to the other under the influence of said spring, and continuously engaged cam connections between the opposing ends of said sections.

2. In valve mechanism wherein is provided a valve and an actuating cam shaft, and a connection between said valve and cam shaft; said connection including a tubular outer unit and an inner unit fitted into the outer unit, said inner unit comprising two axially aligned sections, a torsion spring connecting said sections, means limiting the movement of one section relatively to the other under the influence of said spring, and continuously engaged cam connections between the opposing ends of said sections, said cam connections comprising opposed concave seats on the adjacent ends of said sections and balls located between said seats.

3. In valve mechanism wherein is provided a cam shaft and a valve; an operating connection between the same which includes an outer tubular member closed at one end, an inner unit fitted within said member to seat on said closed end, said inner unit comprising two axially aligned sections rotatable on their common axis as a unit in said tubular member and having limited rotation relatively one to the other, means continuously tending to turn said sections relatively one to the other in one direction, and camming elements between said sections for moving them along their common axis away from one another under the action of said continuously tending means, said camming elements maintaining a contact continuity between the ends of all sections at all times for the purposes specified.

4. In valve mechanism wherein is provided a cam shaft and a valve; an operating connection between the same which includes an outer tubular member closed at one end, an inner unit fitted within said member to seat on said closed end, said inner unit comprising two axially aligned sections rotatable on their common axis as a unit in said tubular member and having limited rotation relatively one to the other means continuously tending to turn said sections relatively one to the other in one direction, and camming elements between said sections for moving them along their common axis away from one another under the action of said continuously tending means, said camming elements comprising opposed concave seats on said sections and bearing balls in said seats.

5. In a valve mechanism wherein is provided a cam shaft and a valve; an operating connection between the same which includes a tappet comprising a shell, an inner unit slidably and swivelly fitted within the shell,

5 said shell having a bottom on which said unit rests, said unit comprising a plurality of axially aligned sections, one having a stem and the other having a passage to receive said stem, a torsion spring in said other section having one end anchored to said other section and its other end anchored to said stem, means to limit the swivelling action of said sections on their common axis under the influence of said spring, the opposing faces of 10 said sections having concave ball seats and balls in said seats.
